UNITED STATES PATENT OFFICE.

WILLIAM RUMBLE, OF NEW YORK, N. Y.

AIR-SHIP.

No. 909,681.

Specification of Letters Patent.

Patented Jan. 12, 1909.

Application filed September 10, 1908. Serial No. 452,879.

To all whom it may concern:

Be it known that I, WILLIAM RUMBLE, a citizen of the United States, and a resident of the city of New York, borough of the Bronx, in the county and State of New York, have invented a new and Improved Air-Ship, of which the following is a full, clear, and exact description.

This invention resides primarily in an improved means to offset the reacting force in driving revoluble propellers, tending to revolve the car of an airship in a reverse direction from that of the propellers' rotation, more especially such propellers as serve

to lift the car.

The purpose of the invention is to provide a casing surrounding the propeller and in connection with the car, having means against which the air current generated by the propeller acts, tending to revolve the casing, and the car to which it is connected, in the same direction as the propeller, thus compensating for the reactionary force developed in driving the propeller.

Reference is to be had to the accompanying drawings forming a part of this specification, in which similar characters of reference indicate corresponding parts in both views.

Figure 1 is an elevational view of an airship embodying my improvements, the same being partly in central vertical section; and Fig. 2 is a cross-section through the ship substantially on the line 2—2 of Fig. 1.

In the construction of my improved ship, I employ a car 5, of any suitable shape or character, to carry, in addition to the aviator, the means for supplying an actuating fluid to the motor, this means in the present embodiment consisting of a boiler 6 which is supplied with liquid fuel from the tanks 7, 7, the latter being supported on a framework and arranged at each side of the boiler, on in any other manner preferred. The steam pipe from the boiler extends upwardly from its center and is provided with a valve 8 for controlling the passage of the steam to a motor 9, the casing of which is also carried by the steam pipe. The rotor of the motor within the motor casing is attached to a vertical shaft 10, which is journaled in the casing, and is provided thereabove with a propeller 11, the same being of well-known

type. The shaft 10 is extended above the propeller and has a collar 12 journaled thereon between two fixed collars, the collar 12 being provided with ties 13 attached to the casing 14, which surrounds the propeller 11, the motor casing 9, the boiler 6, and the car 5. Below the propeller 11, the casing 14 has a number of openings, over which are placed at the outside, vanes or blades 15, each blade being pivotally supported to swing outwardly from the casing, and having an extended portion 16 at the opposite side of its pivot, through which a bolt 17 extends for adjusting the blade to any desired inclination with respect to the casing 14, within certain limits. Below the blades 15, the diameter of the casing is contracted by a conical portion 18, the casing being extended in true cylindrical form below the conical portion, in order to enforce the air passing from the propeller to leave the casing in a vertical direction, this portion of the casing being preferably provided with inner spiral vanes 21 operating under the downward current of air from the propeller, to assist the vanes 15 in revolving the casing in the same direction. The casing 14 is fixed to the motor casing 9 by a spider 19, and is connected with the shaft 10 not only through the ties 13, but directly above the propeller by a spider 20, in which the shaft 10 is journaled.

In the operation of the ship, the steam is admitted to the motor 9, which is preferably of turbine construction, by opening the valve 8, causing the propeller to revolve in the direction indicated by the arrow in Fig. 2. The air current generated by the propeller in moving downwardly is partially compressed by the contraction of the casing, and enforced to travel out through the openings in the side thereof impinging on the blades 15. The inclination of these blades relative to the direction of the rotation of the propeller is such as to tend to revolve the casing in the same direction as the propeller and thus overcome the reacting force of the steam on the motor casing 9 and prevent it and the car from revolving relatively to the earth. By adjusting the inclination of the blades 15, the required power tending to revolve the casing with the propeller to exactly neutralize reactionary force of the

motor, may be arrived at and in this manner no rotation of the car relatively to the earth takes place whatsoever.

Having thus described my invention, I claim as new and desire to secure by Letters Patent:

1. The combination of a casing, a propeller revoluble relatively to the casing, and means carried by the casing and operated by the current of air generated by the propeller, tending to rotate the casing in the same direction as the propeller.

2. The combination of a shaft, a propeller fixed to the shaft, a motor for driving the propeller having a casing, and a casing surrounding the propeller and connected to the motor casing, having means actuated by the air from the propeller, tending to revolve both of said casings in the same direction as the propeller.

3. The combination of a motor having a revoluble member and a non-revoluble member, a shaft fixed to the revoluble member and journaled in the non-revoluble member, a propeller secured to the shaft, and a casing surrounding the propeller and secured to the non-revoluble member of the motor, having means actuated by the current of air generated by the propeller, tending to revolve it in the same direction as the propeller.

4. The combination of a propeller, a casing surrounding the propeller having an opening in the side thereof, and a blade carried by the casing and arranged over said opening, inclining outwardly from the casing in a direction reverse to the revolution of the propeller.

5. The combination of a propeller, a casing surrounding the propeller, having means at the outside thereof and means at the inside thereof tending, under the current of air from the propeller, to revolve the casing in the same direction as the propeller.

6. The combination of a propeller, a casing surrounding the propeller, having an opening in the side thereof, a blade overlying said opening and inclining outwardly

from the casing, and means for adjusting the inclination of the blade.

7. The combination of a propeller, a casing surrounding the propeller, having a contracted lower portion and provided with openings above said contracted portion, and blades carried by the casing and overlying said openings tending to drive the casing under the influence of the air from the propeller in the same direction as the propeller.

8. The combination of a propeller, a casing through which the current of air generated by the propeller passes, and having an opening in the side thereof, and a blade overlying said opening, inclining in a direction to tend to rotate the casing under the influence of said current, in the same direction as the propeller.

9. The combination of a shaft, a propeller fixed to the shaft, a motor having a rotor connected to the shaft, a casing through which the current of air generated by the propeller passes, attached to the motor casing, and means carried by the casing, operated by the air current from the propeller, tending to revolve said casing and motor casing in the same direction as the propeller.

10. The combination of a car, a steam boiler carried by the car, having an upright steam pipe, a turbine motor carried by said pipe, a shaft connected with the rotor of the motor, a propeller carried by the shaft, a casing surrounding the propeller and secured to a fixed portion of the motor and provided with openings in the side thereof, blades carried by the casing, overlying said openings and inclining in a direction to tend to revolve the casing in the same direction as the propeller under the influence of the current of air generated by the propeller and passing through said openings.

In testimony whereof I have signed my name to this specification in the presence of two subscribing witnesses.

WILLIAM RUMBLE.
